TAPE-DISPENSING MACHINE

Alfred P. Krueger, Stratford, Conn., assignor to
 Derby Sealers, Incorporated, Derby, Conn., a
 corporation of Connecticut

Application March 8, 1945, Serial No. 581,637

20 Claims. (Cl. 164—49)

This invention relates to tape-serving machines, and more particularly to a device to deliver a strip of gummed tape of the desired length for sealing packages, parcels, boxes, or the like, which tape is commonly made of paper and usually is furnished in the form of a roll containing a continuous strip, the tape being gummed upon one surface and being fed over a moistening device and severed so that the severed strip is ready for application to the package.

Such devices as the present invention relates to usually are provided with feed rolls for contacting the tape upon its upper and lower surfaces to propel it over the moistening means, and are also provided with a severing device of some kind, such as a knife, which may be automatically operated, or operated by the same element which operates the feed rolls. It is usually convenient to provide an oscillating lever having a forward and rear stroke to actuate the feeding mechanism, the strip being fed forwardly upon the forward stroke of the lever. The severing device may be actuated either at the end of the forward stroke of the lever or at the end of the return stroke, but in either event it will be actuated after a strip of tape of measured length has been fed from the machine.

It is necessary to arrest the feeding means during the operation of the severing means, and if the severing means, as in the present case, is constituted by a knife or cutter movable across the path of the tape strip, the feeding means must be arrested not only during its cutting stroke but also during its return stroke, so that the resumption of the feeding of the tape after a severing operation will not take place until the knife has returned to its original position out of the path of the tape.

In such mechanisms the operating lever usually has a one-way connection with the feed mechanism, and it will be seen that, owing to the inertia of the parts, there may be an overthrow or continued movement of the feed mechanism after the movement of the hand lever is arrested, as a result of the one-way connection between the two. This might result in the delivery of a strip of tape longer than is desired, and it is, therefore, necessary to arrest the feeding mechanism at the proper time in order to insure that the delivered strip will be of the desired length.

When the severing operation takes place at the end of the return stroke, it is usually desirable to have at the rear end of the stroke a

5 certain amount of lost motion of the hand lever so that when this lever begins its forward stroke, strip feeding will not be immediately resumed but will be delayed until the cutter or knife has an opportunity to return to its position of rest and clear the path of the tape.

One object of the present invention is to provide a new and improved tape-dispensing device of the character described.

A further object of the invention is to provide a tape-serving device having all of the functions commonly desired in such a machine, but which may at the same time be economically manufactured and be efficient in operation.

A still further object of the invention is to provide a tape-serving machine having an oscillating operating lever and a severing device, which will serve to sever the tape either at the end of a forward stroke of the lever or at the end of the return stroke of the lever, as desired by the operator.

A still further object of the invention is to provide a tape-serving device of the character described which may be adjusted to sever the tape either at the end of the forward stroke or at the end of the return stroke of the operating lever, as desired by the operator, and at the same time deliver a strip of tape of desired length.

A still further object of the invention is to provide a tape-serving mechanism of the character described in which the feeding mechanism will be positively arrested at the end of a feeding stroke of the actuating lever, so as to avoid overthrow of the parts whereby the delivered strip will be of the desired length.

To these and other ends the invention consists in the novel features and combinations of parts to be hereinafter described and claimed.

In the drawings:

40 Fig. 1 is a side elevational view of a tape-serving machine embodying my invention;

Fig. 2 is a similar view of the machine from the opposite side;

Fig. 3 is a top plan view of the front end portion of the machine, showing the feeding mechanism;

Fig. 4 is a sectional view through the forward portion of the machine;

Fig. 5 is a view similar to Fig. 4, showing the severing knife in its operative position just after the completion of the severing operation;

Fig. 6 is an enlarged partial side elevational view of the device, showing the drive mechanism;

Fig. 7 is a view similar to Fig. 6, showing the parts in another position;

Fig. 8 is a sectional view on line 8—8 of Fig. 6;

Fig. 9 is a view similar to Fig. 6, showing a modified form of drive mechanism;

Fig. 10 is a view of the drive mechanism from the reverse side; and

Fig. 11 is a sectional view on line 11—11 of Fig. 9.

To illustrate a preferred embodiment of my invention I have shown a tape-serving mechanism comprising a frame or basket 10 adjacent the front portion of which is a receptacle 11 adapted to be filled with water or the like, and having therein a moistening brush 12 over which the tape is delivered between guide plates 13 and 14. As the above parts may be of usual form, further description thereof is unnecessary.

Mounted between the side walls of the frame, adjacent the forward part of the machine, is a supporting table 15 over which the tape is fed, and upon which table rests a pressure plate 16 above the upper surface of the tape.

The tape is designed to be fed forwardly through upper and lower feed rolls 17 and 18, the lower of these two rolls being carried by a shaft 19 rotatably mounted in the frame and carrying at one end a pinion 20 (Fig. 6) by which this shaft and the feed roll thereon may be driven. The upper feed roll 17 is mounted upon a shaft 21 carried by arms 22 (one at each side of the device), which arms are swingingly mounted upon a rod 23 extending transversely across the frame.

The upper feed roll 17 is yieldingly pressed downwardly upon the lower roll by means of springs 24, the intermediate portions of which engage the shaft 21 and the ends of which are engaged respectively with a rod 25 supported by the frame 10 and studs 26 extending inwardly from the arms 22. Thus it will be seen that the roller 17 is at all times yieldingly held in feeding relation against the roll 18, so that whenever the latter is rotated tape will be fed forwardly toward the moistening element. The springs 24 permit the roller 17 to yield upwardly slightly in order to allow the operator to insert the tape between the feed rolls when a new roll of tape is introduced into the machine, as is usual with machines of this character.

Rotatably mounted in the side plates of the frame 10 is a main drive shaft 30 having secured at one end an operating handle or lever 31 designed to be oscillated to actuate the lower feed roll 18. The handle 31 is secured at one side of the main frame of the machine, and at the other side of the frame is mounted a drive mechanism connecting this shaft with the pinion 20 which is on the lower feed roll shaft 19.

This drive mechanism comprises a gear 32 loosely mounted upon the shaft 30, the teeth of which mesh with a pinion 33 mounted on a shaft 34 on the frame of the machine, and secured to or formed integrally with a gear 35 the teeth of which mesh with the pinion 20. The novel drive mechanism which connects the shaft 30 with the gear 32 so as to drive the latter in one direction will now be described.

Loosely mounted upon the shaft 30 between the frame of the machine and the gear 32 is a driving or actuating arm 36 rotatably carrying a pinion 37 the teeth of which mesh with those of the gear 32, so that, as this actuating arm is oscillated, the pinion 37 will travel over the gear 32 unless it is held against rotation, in which event it will drive the gear 32 in the direction in which it is moved.

A second arm 38 is secured to the shaft 30 and is provided at its upper end with an abutment 39

extending over the gear 32 so as to engage the face of the arm 36. Also loosely mounted on the shaft 30 is a third arm 40 having on the rear face thereof a dog or detent 41 adapted to engage between the teeth of the pinion 37 and prevent the rotation of this pinion, while at the same time drawing the arm 36 forwardly. A spring 42 is mounted between posts 43 and 44 on the arms 38 and 40, and tends to draw these arms together as closely as is permitted by the adjustable stop 45 pivoted to the arm 38 at 46.

A stop 47 is provided on the frame to contact the arm 36 and arrest its forward motion, and a stop 48 is also provided on the frame to contact this arm and arrest its rearward motion. As will be later explained, one of these stops will be used when the severing action takes place at the forward end of the stroke, while the other will be used when the cutting action takes place at the rear end of the stroke.

As shown in Fig. 2, a bracket 49 is mounted on the frame 10 adjacent the lever or handle 31, this bracket being provided with an arcuate slot 50 in which are mounted adjustable stops 51 and 52, so that these stops may be set at any desired place along the slot 50. It will be understood that when the cutting action takes place at the forward end of the stroke it will not be desired to limit the forward movement of the lever 31 at the end of the feeding operation, and at this time the stop 52 will be at the extreme forward end of the slot 50, where it acts as a stop for the lever at the conclusion of the cutting operation. At this time the stop 51 will be positioned, as shown in Fig. 2, to limit the return stroke of the lever so that no cutting will take place at the end of the return stroke. In this position the maximum length of strip of tape which can be served at a single stroke will be obtained. It will be understood that this stop 51 may be moved forwardly to any desired point to serve shorter strips. When, however, the cutting takes place at the rear end of the stroke, the stop 52 will be set at the proper place along the bracket 49 to stop the forward stroke just prior to the beginning of the severing operation. This gives the maximum length of strip which can be served at a single stroke, and if shorter lengths are desired the stop 52 will be moved rearwardly to the proper position. At this time the stop 51 will be moved to the rear end of the slot 50 and will serve as a stop for the lever at the end of the cutting operation.

The severing mechanism comprises a knife or cutter frame comprising a pair of arms 55, one mounted adjacent each side wall of the frame, which arms are pivoted upon the rod 25 and connected at their forward ends by a knife bar 56 carrying the severing blade 57. Each of the arms 55 is provided with a depending plate 58, which plates are connected by transversely extending bars 59 in order to form a rigid frame. Secured to the shaft 30 are cutter-actuating cams or lugs 60, one adjacent each end of the shaft within the frame 10, and these lugs are adapted at the end of the back stroke or return stroke of the handle 31 to contact one of the bars 59 and swing the cutter about the rod 25 from its inoperative position, shown in Fig. 4, to the position shown in Fig. 5, during which movement the tape will be severed against the forward end of the table 15. A pair of coiled springs 62, one at each side of the device, are connected at one end to a member 63 on the cutter frame 55, and at the other end, as shown at 64, to the lugs 60, the intermediate portion of each spring being passed around a sheave

65 loosely mounted upon the shaft 34. Thus the springs 62 serve the double purpose of maintaining the handle in its rearward position, or in position to begin the feeding stroke, and also maintain the knife blade in its upper inoperative position, shown in Fig. 4.

As will be obvious, the lugs 60 strike the bar 59 to operate the knife blade at the end of the return stroke, and beyond or rearwardly of the position at which feeding is initiated upon the forward stroke of the lever 31. In order that the knife may also be operated, if desired, at the end of a forward stroke of the operating lever, a stirrup 66 is connected at its upper ends to the arms 55 of the knife and depends downwardly, as shown in Figs. 4 and 5, to a position where the body portion of the stirrup will be engaged by the lugs 60, as shown in dotted lines in Fig. 5, so as to swing the knife frame downwardly about the pivot 25 and effect an operative stroke of the cutting blade 51. It will, of course, be understood that, as will be described hereinafter, the feeding of the strip will be interrupted prior to the operation of the cutter at the forward stroke of the lever.

As described above, the pinion 37 is rotatably mounted on the arm 36 by means of a headed pin 61, and this pinion may be frictionally restrained against rotation by means of a relatively light compression spring 68 acting between the head of the pin and the pinion (Fig. 8).

It will be recalled that the arm 38 is fixed to the shaft 30 so that this arm constitutes the driving member for the feed mechanism, as it is oscillated or moved with the hand lever 31. When the device is set to cut at the end of the forward stroke of the lever 31, the parts will normally stand in the position shown in Figs. 4 and 6 when the device is at rest. If the handle 31 is moved forwardly from this position, the arm 38 will be rotated in a counterclockwise direction, as shown in Fig. 6, and will draw along with it the arm 40 due to the spring 42 connecting these two arms, this spring being sufficiently strong to exert an effort sufficient to effect the normal feeding operation without being stretched to any appreciable extent. When the arm 40 moves forwardly, the dog 41 will engage between the teeth of the pinion 37, and thus restrain this pinion against rotation, while at the same time drawing the arm 36 forwardly along with the arm 40. This will effect rotation of the gear 32 and thus effect the feeding operation.

The forward stroke of the lever 31 will cause the arm 36 to strike the stop 47 and be arrested by this stop, thus checking the feeding movement of the parts. This position is shown in dotted lines in Fig. 6, where it will be noted that the dog or lug 41 is engaged between the teeth of the pinion 37, and the arm 36 is against the stop 47. Thus the pinion 37 will also be held against rotation so that the gear 32 will be positively held against rotation and prevent any overthrow movement which would tend to feed an additional length of strip. Continued movement of the lever 31 moves the arm 38 to the dotted line position shown in Fig. 6 without further movement of the arm 36, this being allowed by the extension of the spring 42, and this additional movement serves to engage the lugs 60 with the stirrup 66 and effect the operation of the severing blade 51. This severing operation is, as stated, effected while the arm 36 is at rest against the stop 47, so that during this operation any feeding is positively prevented by the engagement of the dog 41 with the pinion 37.

The handle 31 will then be released by the operator and will be returned sharply by the springs 62. At the beginning of this movement the spring 42 will contract to its original length, bringing the inner end of the stop 45 against the arm 40, at which time the dog 41 will withdraw from the teeth of the pinion 37, and the lug 39 on the arm 38 will contact the forward or under face of the arm 36 and thus move the arm 36 rearwardly, but at the same time permit the pinion 37 to rotate about the periphery of the gear 32 so that the latter will remain at rest. It will be understood that there is a slight lost motion between the arm 36 on the one hand and the abutments 39 and 41 on the other hand to permit the latter to withdraw from the teeth of the pinion just prior to the engagement of the abutment 39 with the arm 36. Hence during the return stroke of the lever 31 there will be no movement of the gear 32, the retarding effect of the spring 68 on the pinion 37 not being sufficient to operate the gear train. The lever 31 will be returned by the spring 62 against the stop 51 at the rear of the bracket 49, which stop will be set to determine the beginning of the forward feeding motion of the device so as to measure the length of the severed strip. At this time the front stop 52 will not be employed to limit the feed, as the forward feeding motion will be arrested by the engagement of the stop 47 with the arm 36.

When it is desired to sever the strip at the rear end of the return stroke, the stop 45 is turned about the pivot 46 from the position shown in Fig. 6 to that shown in Fig. 7, thus separating the arms 38 and 40 to a further extent against the tension of the spring 42. It may be noted that at this time the spring 42 may be disregarded, as the arms 38 and 40 are held at all times in their relative positions, shown in Fig. 7. This provides a greater amount of lost motion between the arms 38 and 40 and the arm 36, which will serve to permit a sufficient range of movement at the rear of the return stroke to effect the cutting operation without feeding the tape.

The stop 50 will now be adjusted along the slot 50 to arrest the feeding movement, and thus measure the served strip. As shown in Fig. 7 of the drawings, the parts are in the position assumed at the rear end of the back stroke after the cutting operation has taken place. When the lever 31 is moved forwardly, no movement of the arm 36 will be effected until the dog 41 is moved to a sufficient extent to engage the teeth of the pinion 37. This permits the lugs 60 to disengage the bar 59 and permit the knife to swing upwardly out of the path of the tape before the initiation of the feeding operation. When the dog 41 engages the teeth of the pinion 36, feeding will be initiated as before, and will be continued until the lever 31 strikes the stop 52. The lever will then be released and the parts returned by the springs 62, the return stroke of the lever being arrested by the engagement of this member with a felt collar 10 (Fig. 3) on the stop member 54, although it will be understood that this stop will be set beyond the feeding range of the lever. At about the same time the rearward movement of the arm 36 will be arrested by the stop 48, so that this arm cannot overthrow rearwardly against the dog 41, thus holding the arm 36 in the position shown in Fig. 7 to provide for the raising of the knife, as described, before the dog 41 can again contact the pinion 37. During the latter part of this return movement, prior to the engagement of the lever arm 31 with the

stop 51, the severing mechanism will be actuated by the lug 60 striking the bar 59, and thus effect the severing of the strip.

It will be noted that the mechanism shown can be employed either as a front-cut machine or a rear-cut machine, as desired, merely by proper adjustment of the stops 51 and 52 and the changing of the spacing between the arms 38 and 40 by means of the pivoted stop 45.

In Figs. 9, 10 and 11 of the drawings I have shown a modified form of drive mechanism adapted for use when the mechanism is designed to sever the strip at the end of the forward stroke. In this form of my invention the shaft 30, gear 32, pinion 33 and shaft 34 are all arranged as above described in connection with the modification shown in Figs. 1 to 8. Between the gear 32 and the frame 10 a driving arm 75 is secured to the shaft 30, which arm corresponds to the driving arm 38 previously described. On the other side of the gear 32 an arm 76 is mounted loosely on the shaft 30, this arm carrying a dog 77 adapted to engage the teeth of a pinion 78 rotatably mounted on a pin 79 carried by an arm 80 also loosely mounted on the shaft 30 forwardly of the arm 76. As shown in Fig. 11, the pinion 78 is spaced from the arm 80 by the spacing collar 81 so that it will lie in the plane of the gear 32 and mesh with the teeth of this gear.

As best shown in Fig. 10, a latch member 82 is pivoted at 83 to an arm 75, this latch member being provided with a recess 84 adapted to embrace an inwardly projecting stud 85 on the arm 76, so that, when the stud is engaged in the recess, the arms 75 and 76 will be locked together.

The latch member 82 is urged into engagement with the stud 85 by a spring 86 secured at one end to the latch member and at the other end to the arm 75, and a spring 87 extends between the pin 83 and the stud 85, which spring tends to urge these arms toward each other, as permitted by the latch member 82. It will be noted that the lower lip 88 of the recess projects outwardly so that it will catch upon the adjacent edge of the stud 85 when the arms 75 and 76 are drawn together by the spring 87.

The latch member 82 is provided with a cam or tail portion 90 designed to be engaged by a stop 91 on the frame 10 of the machine, when the arm 75 is moved to its forward position in the feeding operation. When the stop 91 strikes the tail portion 90 of the latch member, the latter will be cammed in a counterclockwise direction about its pivot 83, as shown in Fig. 10, so as to disengage the recess 84 from the post 85 and thus release the arm 76. This occurs at the end of the feeding stroke of the parts, and at this time the pin 79 on the arm 80 strikes a stop 92 on the frame of the machine so that further movement of the arm 80, and therefore of the pinion 78 and gear 32, is prevented. However, as the driving arm 75 is now unlatched from the arm 76, the former may continue its movement against the tension of the spring 87 to effect the severing of the strip while the feeding mechanism is at rest. It will be understood that the severing will be effected by the means shown in Figs. 4 and 5 of the drawings.

The pin 79 which carries the pinion 78 is extended inwardly beyond the gear 32 and serves as an abutment against which the arm 75 may bear to return the parts during the return stroke of the lever 31 and shaft 30.

The operation of this form of my invention may now be described. With the parts occupying the

position shown in full lines in Fig. 9, the device is ready to begin an operative cycle. The shaft 30 is oscillated by the handle or lever 31, and as the arm 75 is secured rigidly to this shaft it will also be oscillated. At this time the arm 76, which is latched to the arm 75 by the latch member 82, will also be moved forwardly, and the dog 77 will engage the teeth of the pinion 78, preventing the rotation of the pinion and also moving the arm 80 forwardly so as to rotate the gear 32. The feeding of the strip is thus initiated and continues until the pin 79 strikes the stop 92, and this arrests the movement of the arm 80. This position of the parts is shown in dotted line position in Fig. 9, where it will be noted that the dog 77 is between the teeth of the pinion 78, thus locking the gear 32 against overthrow.

Just prior to contact of the pin 79 with the stop 92, the tail portion 90 of the latch 82 engages the stop 91 and throws the latch 82 into the position shown in Fig. 10, in which the recess 84 is disengaged from the post 85, thus permitting the arms 75 and 76 to separate against the tension of the spring 87, and permit the shaft 30 to continue its rotation to effect the severing operation. It will be understood that during this continued movement the arm 75 moves away from the arms 80 and 76, which will remain in the dotted line position shown in Fig. 9.

At the end of the severing operation the operator releases the lever 31, which is returned to its rearward position by the springs 62. Upon the beginning of this rearward movement of the lever 31 and arm 75, the tail 90 of the latch is moved about its pivot by the spring 86 so that the shoulder 88 engages below the post 85 and insures the entry of the latter into the recess 84. At this time the arm 75 picks up the arm 76 through the agency of the latch 82, and also picks up the arm 80 by engagement with the extended end of the pin 79 so that the three arms are returned together to the full-line position shown in Fig. 9. It will be understood that there is a slight lost motion between the arms 75 and 76 on the one hand and the arm 80 on the other, so that, at the beginning of the return movement of the parts, the dog 77 will move out of engagement with the teeth of the pinion 78 prior to the picking up of the arm 80 by the arm 75 so that the pinion 78 will be permitted to rotate idly over the periphery of the gear 32 and the latter remain at rest during the return movement of the parts.

While I have shown and described some preferred embodiments of my invention, it will be understood that it is not to be limited to all of the details shown, but is capable of modification and variation within the spirit of the invention and within the scope of the claims.

What I claim is:

1. A tape-dispensing machine comprising means for feeding the tape forwardly, an oscillatable driving member by which power is applied to feed the tape, said member having a one-way drive connection with said feeding means, and means for positively locking said feeding means against overthrow at the end of the feeding stroke of said member.

2. A tape-dispensing machine comprising means for feeding the tape forwardly, an oscillatable driving member by which power is applied to feed the tape, said member having a one-way drive connection with said feeding means, and automatically acting means for positively locking said

feeding means against overthrow at the end of the feeding stroke of said member.

3. A tape-dispensing machine comprising means for feeding the tape forwardly, an oscillatable driving member by which power is applied to feed the tape, a drive gear for said feeding means, said member having a one-way drive connection with said drive gear, and means for instantly and positively locking said gear against rotation at the end of a feeding stroke of said member.

4. A tape-dispensing machine comprising means for feeding the tape forwardly, an oscillatable driving member by which power is applied to feed the tape, a drive gear for said feeding means, said member having a one-way drive connection with said drive gear, and means for positively locking said gear against rotation at the end of the feeding stroke of said member, said connection including means permitting additional movement of said member in the same direction after the rotation of said gear is checked.

5. A tape-dispensing machine comprising means for feeding the tape forwardly, an oscillatable driving member by which power is applied to feed the tape, an actuating arm connected to said feeding means to drive the same when the arm is moved in one direction, means to check the movement of said arm and simultaneously and positively lock the feeding means against overthrow, and an operative connection between said driving member and said arm.

6. A tape-dispensing machine comprising means for feeding the tape forwardly, an oscillatable driving member by which power is applied to feed the tape, an actuating arm connected to said feeding means to drive the same when the arm is moved in one direction, means to check the movement of said arm and simultaneously and positively lock the feeding means against overthrow, and a lost-motion connection between said driving member and said arm permitting additional forward movement of the driving member after the movement of said arm is checked.

7. A tape-dispensing machine comprising means for feeding the tape forwardly, an oscillatable driving member by which power is applied to feed the tape, an actuating arm connected to said feeding means to drive the same when the arm is moved in one direction, means to check the movement of said arm and simultaneously and positively lock the feeding means against overthrow, a lost-motion connection between said driving member and said arm permitting additional forward movement of the driving member after the movement of said arm is checked, a severing device, and means for actuating said device by said additional movement of the driving member after the checking of said arm.

8. In a tape-dispensing machine, feed rolls between which the tape is fed forwardly, an oscillatable driving member through which power is applied to feed the tape, means connecting said member to one of said rolls, said means comprising an actuator connected to said roll to rotate the latter upon the forward movement of the actuator, means connecting said member to the actuator to move the latter in both directions comprising an abutment at each side of the actuator, and means for adjusting the spacing of said abutments to vary the lost motion between said actuating arm and said abutments.

9. In a tape-dispensing machine, feed rolls between which the tape is fed forwardly, an oscillatable driving member through which power is

applied to feed the tape, means connecting said member to one of said rolls, said means comprising an actuator connected to said roll to rotate the latter upon the forward movement of the actuator, means connecting said member to the actuator to move the latter in both directions comprising an abutment at each side of the actuator, means for adjusting the spacing of said abutments to vary the lost motion between said actuating arm and said abutments, stop means engaging said arm at either end of its stroke, and cutting means operable by said driving means at either end of its stroke.

10. A tape-dispensing machine comprising feeding rolls between which the tape is advanced, a drive gear operatively connected to one of said rolls to rotate the latter, means to drive said gear comprising an actuating arm pivoted on the axis of the gear and carrying a pinion meshing with the gear, drive mechanism oscillatable about said gear axis and having an abutment on each side of said arm, said abutments being spaced apart to permit lost motion between said mechanism and said arm at each end of the stroke, and means checking the forward movement of said arm while holding said pinion against rotation.

11. A tape-dispensing machine comprising feeding rolls between which the tape is advanced, a drive gear operatively connected to one of said rolls to rotate the latter, means to drive said gear comprising an actuating arm pivoted on the axis of the gear and carrying a pinion meshing with the gear, drive mechanism oscillatable about said gear axis and having an abutment on each side of said arm, said abutments being spaced apart to permit lost motion between said mechanism and said arm at each end of the stroke, and severing means operable by said drive mechanism at either end of the stroke.

12. A tape-dispensing machine comprising feeding rolls between which the tape is advanced, a drive gear operatively connected to one of said rolls to rotate the latter, means to drive said gear comprising an actuating arm pivoted on the axis of the gear and carrying a pinion meshing with the gear, drive mechanism oscillatable about said gear axis and having an abutment on one side of said arm and a dog to engage the teeth of the pinion on the other side of said arm, means providing relative movement between said arm and drive mechanism to disengage the dog from the pinion when the abutment engages the arm, and means for engaging said arm to check the forward movement thereof while said dog holds said pinion against movement.

13. A tape-dispensing machine comprising feeding rolls between which the tape is advanced, a drive gear operatively connected to one of said rolls to rotate the latter, means to drive said gear comprising an oscillatable driving member, an arm pivoted on the axis of said member and having means to engage the teeth of the gear, a second arm pivoted on the axis of the driving member and engaging said first arm at one side thereof, said driving member engaging said first arm on the other side thereof, and an extensible spring joining said driving member and said second arm and serving to move the latter in a feeding direction when said driving member is moved forwardly.

14. A tape-dispensing machine comprising feeding rolls between which the tape is advanced, a drive gear operatively connected to one of said rolls to rotate the latter, means to drive said gear comprising an oscillatable driving member, an

arm pivoted on the axis of said member and having means to engage the teeth of the gear, a second arm pivoted on the axis of the driving member and engaging said first arm at one side thereof, said driving member engaging said first arm on the other side thereof, an extensible spring joining said driving member and said second arm and serving to move the latter in a feeding direction when said driving member is moved forwardly, means to check the movement of said first-named arm at the end of a forward stroke thereof, severing means, and means to actuate said severing means by an additional movement of said driving member after the movement of said first arm is checked.

15. A tape-dispensing machine comprising feed rolls between which the tape is advanced, a drive gear operatively connected to one of said rolls to rotate the latter, a pivotally mounted actuating arm having a one-way connection with said gear, an oscillatable driving member engaging one side of said arm to move the same in one direction, a second arm on the side of said first arm to move the latter in the opposite direction, an extensible spring connecting said second arm to said driving member and urging it toward the latter, and adjustable means holding said driving member and said second arm in spaced relation against the tension of said spring.

16. A tape-dispensing machine comprising feed rolls between which the tape is fed forwardly, an oscillatable drive shaft, connecting means between said shaft and rolls to drive the latter, severing means comprising a knife frame and a knife carried thereby, spaced actuating members on said frame, and means on said drive shaft for engaging either of said members to actuate the severing means.

17. A tape-dispensing machine comprising feed rolls between which the tape is fed forwardly, an oscillatable drive shaft, connecting means between said shaft and rolls to drive the latter, severing means comprising a knife frame and a knife carried thereby, spaced actuating members on said frame, and means on said drive shaft for engaging either of said members to actuate the severing means, said means engaging one of said members at the forward end of the movement of the drive shaft and the other member at the rear end of such movement.

18. A tape-dispensing machine comprising means for feeding the tape forwardly, an oscillatable driving member by which power is applied to feed the tape, said feeding means including a drive gear, an arm connected with said gear to drive the same in one direction, stop means checking the forward movement of said arm, a latch member carried by the driving member and engaged with said arm, and means engaging said latch member adjacent the end of a forward stroke of the arm to disengage the latch member from the arm and permit additional forward movement of the driving member independently of the arm.

19. A tape-dispensing machine comprising means for feeding the tape forwardly, an oscillatable driving member by which power is applied to feed the tape, said feeding means including a drive gear, an arm connected with said gear to drive the same in one direction, stop means checking the forward movement of said arm, a latch member carried by the driving member and engaged with said arm, means engaging said latch member adjacent the end of a forward stroke of the arm to disengage the latch member from the arm and permit additional forward movement of the driving member independently of the arm, and means for locking the feeding means against overthrow upon disengagement of the latch member from said arm.

20. A tape-dispensing machine comprising means for feeding the tape forwardly, an oscillatable driving member by which power is applied to feed the tape, said feeding means including a drive gear, an arm connected with said gear to drive the same in one direction, a latch member carried by the driving member and engaged with said arm, said engagement comprising a recess in said latch member and a post on the arm, means engaging said latch member adjacent the end of a forward stroke of the arm to effect disengagement of the post from said recess, and one edge of said recess projecting beyond the other edge thereof to insure reengagement of the post in said recess when the latch member is disengaged from said means.

ALFRED P. KRUEGER.
